STORM SASH VENTILATOR

Martin H. Ave'Lallemand, Milwaukee, Wis.

Application December 10, 1941, Serial No. 422,423

6 Claims. (Cl. 98—97)

The present invention relates generally to improvements in the art of ventilation, and relates more specifically to improvements in the construction and operation of ventilating devices especially adapted for cooperation with storm sash or other building closures.

An object of the invention is to provide an improved ventilator which is simple in construction and efficient in operation.

It has long been customary in the building industry, to provide ventilators associated with storm sash or the like, for permitting a moderate degree of fresh air ventilation without necessarily opening the storm windows to which the ventilators were applied. These prior storm sash ventilators usually consisted of a series of holes bored through the lower rail of each sash, and a closure plate for the holes pivotally attached to the inner side of the rail laterally beyond one end of the series, the plate being swingably adjustable from a position wherein all of the holes were completely closed, to various positions wherein the holes were more or less uncovered. Since the elongated closure plate of this prior type of regulator was pivotally suspended from end only, usually the right hand end, adjustment of the plate would always necessitate opening of the opposite or left hand end holes of the series before the opposite end holes could be completely opened, thereby eliminating possibility of obtaining uniform or selected distribution of the fresh air supply; and this pivoting of the long closure plate also caused the same to undesirably obstruct the view through the window when all of the vent holes were uncovered. In order to thoroughly clean or paint the lower rail of a window equipped with such a ventilator, it was heretofore necessary to remove the closure plate by unscrewing the pivot; and these prior devices also required the use of considerable unnecessary stock in the formation of the closure plate and the stop plate for limiting the closing movement thereof.

The present invention therefore contemplates provision of a new and useful storm sash ventilator which obviates all of the above mentioned objectionable features of the prior swing plate ventilators, and which can be readily applied and actuated to produce any desired degree of ventilation or distribution of the fresh air.

Another specific object of my invention is to provide an improved window ventilator of the type having one or more slots or openings adapted to be closed by means of an adjustable plate, and wherein the closure plate may be conven-

iently adjusted to open or close any selected portion of the slot or openings of the series in order to obtain the desired conditions of ventilation.

A further specific object of the present invention is to provide an improved storm sash ventilator of the elongated, adjustable closure plate type, and in which any adjustment may be effected without undesirably obstructing the view through the window.

10 Still another specific object of this invention is to provide an improved ventilating device for windows or the like, the major portions of which are readily and quickly detachable or removable in order to facilitate cleaning or painting of the window frame or other parts.

An additional specific object of my present invention is to provide an improved ventilator assembly which can be manufactured and sold at moderate cost and without the use of excess material, which can be readily installed and manipulated, and which is highly attractive in appearance.

These and other objects and advantages of the improvement will be apparent from the following detailed description.

A clear conception of one simple embodiment of the invention, and of the mode of constructing, of applying and of manipulating the improved ventilators, may be had by referring to the drawing accompanying and forming a part of this specification wherein like reference characters designate the same or similar parts in the various views.

35 Fig. 1 is a side elevation of one of the improved ventilators applied to a fragment of a window sash, and showing the same completely closed;

Fig. 2 is a similar elevation similarly applied, but showing the regulating plate adjusted to partially open some of the vent holes;

40 Fig. 3 is another similar elevation of the ventilating assembly, but showing the adjustable control plate positioned to uncover all of the vent holes;

45 Fig. 4 is still another similar view of the ventilating device, showing one of the end retainers released to permit free swinging or removal of closure plate;

Fig. 5 is a transverse vertical section through 50 the window and ventilator assemblage, taken along the line 5—5 of Fig. 1; and

Fig. 6 is an enlarged fragmentary section through the ventilator and window rail, taken along the line 6—6 of Fig. 1.

55 While the invention has been shown and de-

scribed herein as having been embodied in a storm sash ventilator having a series of circular vent holes adapted to be covered more or less by a sheet metal closure plate, it is not my desire or intent to thereby unnecessarily restrict the scope or utility of the improvement, since the ventilating appliance may obviously be associated with other types of closures and may be formed of other materials.

Referring to the drawing, the present improved ventilator is readily and conveniently associable with a window sash having a lower rail 7 provided with a horizontal slot or a series of bored holes 8, and being associated with a transparent window pane 9; and the improved ventilator assembly comprises in general an elongated closure plate 10 of sufficient length and breadth to completely cover all of the holes 8, and a pair of oppositely disposed pivotally suspended spring arms 11 secured to the rail 7 by pivot screws 12 and having inwardly directed swinging end projections 13 cooperating with sockets 14 formed in the ends of the plate 10.

As shown in the drawing, the closure plate 10 may be formed of sheet metal with the aid of punches and dies, and when so formed, it is preferable to dish this plate 10 sufficiently to provide an elevated gripping ridge 15 along the edge thereof so as to facilitate adjustment. This plate 10 may however be formed of non-metallic material, and in order to eliminate waste of stock, the closure plate may obviously be reduced in size or area so that it will just cover the vent slots or holes 8 when the plate is in closed position, see Fig. 6. The closure plate 10 of the ventilating assemblage may also be attractively decorated, and the sockets 14 may be circular and preferably do not penetrate the plate 10. The surface or outer edge portion of the plate flange 16 should be formed to snugly engage the adjacent plane surface of the window rail 7 when the plate is in closed position; and the opposite ends of the elongated plate may be either semi-circular as shown, or any other desirable shape, but the plate 10 is preferably of symmetrical contour so that it cannot be improperly assembled.

The plate suspension arms 11 which are pivotally attached to the lower window rail 7 beyond the opposite ends of the series of vent holes 8 by the pivot screws 12, are preferably formed of spring metal, and have their swinging ends biased toward the adjacent surface of the rail 7 so that the integral end projections 13 will be retained within the sockets 14 and the entire plate 10 will be constantly resiliently urged toward the rail 7. The arms 11 are preferably of like and interchangeable construction and may be formed with the aid of punches and dies, and the pivot screws 12 should be so located that they will permit the plate 10 to be positioned either over the holes 8 as in Fig. 1, or entirely free from the vent holes 8 as in Fig. 3, or in any intervening tilted position either inclined to the left or to the right as in Fig. 2. The suspension arms 11 while normally maintaining the ventilator assembled, should be sufficiently flexible so that either or both of them may be readily withdrawn from the plate sockets 14 as shown at the right of Fig. 4, thereby permitting the closure plate 10 to be either swung away from the rail 7, or entirely removed from the window in order to facilitate cleaning or painting. The integral end projections 13 of the suspension arms 11 rather loosely coact with the sockets 14 in order

to avoid binding of the parts, and the pivot screws 12 may be ordinary wood screws.

During normal use of the improved ventilator, after the suspension arms 11 have been properly applied to the sash rail 7 with the aid of the pivot screws 12 and have been caused to properly cooperate with the sockets 14 of the closure plate 10, this plate may be conveniently adjusted to various positions by merely grasping the plate 10 ridge 15. When the ventilator is not in use, the closure plate 10 will be positioned as shown in Figs. 1, 5 and 6, and will thus seal the vent holes 8 in the rail 7. If a moderate degree of ventilation is desired, either end of the closure plate 10 may be swung upwardly to partially uncover the adjacent vent holes 8 as depicted in Fig. 2; and if maximum ventilation is to be effected, the opposite ends of the elongated plate 10 may be elevated in succession so as to place the plate in its highest position as illustrated in Fig. 3 wherein the holes 8 are entirely uncovered. The closure plate 10 may thus be readily adjusted to uncover the vent holes 8 to any desired extent, or to uncover only selected end holes, and the swing links or arms 11 will never permit the plate 10 to move above the top of the lower rail 7 any higher than as shown in Fig. 3. The spring arms 11 normally press the closure plate 10 snugly against the sash rail 7 while permitting convenient sliding of the plate for adjustment purposes; but if it becomes desirable to partially or completely release the closure plate 10, the swing links or arms 11 may be withdrawn from the sockets 14 as shown in Fig. 4, thereby permitting free access to the surfaces normally concealed by the plate 10.

From the foregoing detailed description it will be apparent that my present invention provides an improved ventilator especially applicable to storm sash or the like, which is simple, compact, and durable in construction, and which is moreover highly effective and flexible in use. By forming the closure plate 10 symmetrical as shown, and the suspension arms 11 interchangeably similar, the cost of construction is not only reduced to a minimum, but possibility of error in making installations is also minimized, and the improved assembly can obviously be applied as a unit to practically any standard storm window having either a single elongated vent slot or a series of holes 8 such as shown. The improved ventilator can also be produced with practically no waste of material, and is operable without undesirably obstructing the view through the window; and the closure plate 10 may be quickly and conveniently removed from the suspension arms 11 in order to gain access to the normally concealed surfaces. The device is readily manipulable by virtue of the provision of the shoulder ridge 15, and has proven entirely satisfactory in actual use.

It should be understood that it is not desired to limit this invention to the exact details of construction, or to the precise mode of use, herein shown and described, for various modifications within the scope of the appended claims, may occur to persons skilled in the art.

I claim:

1. In combination with a member having a vent hole terminating in a flat surface, an elongated flat closure plate slidably cooperable with said surface to cover and uncover said hole, and a pair of actuating arms mounted upon the member and being swingable about parallel axes disposed perpendicular to said surface and out-

wardly beyond the opposite extreme ends of said plate, the swinging ends of said arms being pivotally cooperable with the opposite ends of said plate.

2. In combination with a member having an elongated series of vent holes terminating in a common flat surface, an elongated flat closure plate slidably cooperable with said surface to cover and uncover said holes, and a pair of actuating arms mounted upon the member and being swingable about axes disposed perpendicular to said surface and having their swinging ends pivotally cooperable with the opposite ends of said plate, said arms being simultaneously swingable in opposite directions about their pivotal axes to uncover all of said holes.

3. In combination with a member having an elongated series of vent holes terminating in a common flat surface, an elongated flat closure plate slidably cooperable with said surface to cover and uncover said holes, and a pair of actuating arms mounted upon the member and being swingable about axes disposed perpendicular to said surface and having their swinging ends pivotally cooperable with the opposite ends of said plate, said arms being independently swingable about their pivotal axes to uncover only the adjacent holes of said series.

4. In combination with a member having an elongated series of vent holes terminating in a common flat surface, an elongated flat closure plate slidably cooperable with said surface to cover and uncover said holes, and a pair of actuating arms pivotally mounted upon the member and being swingable about parallel axes disposed

perpendicular to said surface and beyond the opposite extreme ends of said plate, the swinging ends of said arms being pivotally and slidably cooperable with the adjacent ends of said plate to permit either simultaneous or independent swinging of the arms.

5. In combination with a member having an elongated series of vent holes terminating in a common flat surface, an elongated flat closure plate slidably cooperable with said surface to cover and uncover said holes, and a pair of actuating arms pivotally mounted upon the member and being swingable about parallel axes disposed perpendicular to said surface and beyond the opposite extreme ends of said plate, the swinging ends of said arms being resiliently biased toward said surface and being engageable with said plate to hold the latter in snug sliding contact with said surface.

6. In combination with a member having an elongated series of vent holes terminating in a common flat surface, an elongated flat closure plate slidably cooperable with said surface to cover and uncover said holes and having sockets in its opposite ends, and a pair of actuating arms pivotally mounted upon the member and being swingable about parallel axes disposed perpendicular to said surface, the swinging ends of said arms being resiliently biased toward said surface and engageable with said sockets to normally hold said plate in snug sliding contact with said surface, and said ends being removable from said sockets to release said plate.
